UNITED STATES PATENT OFFICE.

LUVERNE K. ELLIS, OF DES MOINES, IOWA.

DESIGN FOR AN INDIVIDUAL HOG-HOUSE.

60,087.

Specification for Design.

Patented Dec. 27, 1921.

Application filed July 6, 1920. Serial No. 394,367. Term of patent 3½ years.

To all whom it may concern:

Be it known that I, LUVERNE K. ELLIS, a citizen of the United States, and a resident of Des Moines, in the county of Polk and State of Iowa, have invented a certain new, original, and ornamental Design for an Individual Hog-House, of which the following is a specification, reference being had to the accompanying drawing, forming part thereof.

Figure 1 is a perspective view; and Fig. 2 is an end elevation.

I claim:

The ornamental design for an individual hog house, as shown.

Des Moines, Iowa, June 22, 1920.

LUVERNE K. ELLIS.
